UNITED STATES PATENT OFFICE.

JOHN B. OLSON, OF FORT ATKINSON, WISCONSIN, ASSIGNOR TO JAMES MANUFACTURING CO., OF FORT ATKINSON, WISCONSIN.

DESIGN FOR A POULTRY-FEEDING DEVICE.

Application filed October 23, 1922. Serial No. 4,061. Term of patent 7 years.

To all whom it may concern:

Be it known that I, JOHN B. OLSON, a citizen of the United States, residing at Fort Atkinson, in the county of Jefferson and State of Wisconsin, have invented a new, original, and ornamental Design for Poultry-Feeding Devices, of which the following is a specification, reference being had to the accompanying drawing, forming part thereof.

The drawing is a view in perspective of a poultry feeding device embodying my new design.

I claim:

The ornamental design for a poultry feeding device as shown.

JOHN B. OLSON.
